UNITED STATES PATENT OFFICE.

I. ORVILLE WRIGHT, OF BALTIMORE, AND WILLIAM H. STEM, OF UNION BRIDGE, MARYLAND.

DRAFT AND BUFFING GEAR FOR CARS.

SPECIFICATION forming part of Letters Patent No. 740,349, dated September 29, 1903.

Application filed March 3, 1903. Serial No. 145,888. (No model.)

To all whom it may concern:

Be it known that we, I. ORVILLE WRIGHT, residing at Baltimore, and WILLIAM H. STEM, residing at Union Bridge, in the county of Carroll, State of Maryland, citizens of the United States, have invented new and useful Improvements in Draft and Buffing Gears for Cars, of which the following is a specification.

The object of our invention is the provision of improved means for effectively transforming the momentum of a car or cars in drawing or buffing into the work of compressing a spring or springs and the moving of metallic frictional surfaces one upon another and without injury to the car underframing or body, said means to be simple in construction, efficient in operation, so arranged as to prevent recoil of the spring or springs, comprised of a suitable number of parts so assembled and arranged that repairs may be easily, cheaply, and quickly effected when necessary without taking a car to the shops, which shall be strong and durable and not liable to become deranged or inoperative, and which shall withal constitute a superior means for performing the requisite functions of a perfect draft and buffing gear or rigging.

With this end or purpose in view our invention consists in certain novelties of construction and the arrangement and combination of parts, as hereinafter set forth, and pointed out in the claims.

The accompanying drawings, which form a part of this specification, illustrate two examples of the physical embodiment of our invention constructed according to the best modes we have so far devised for the practical application of the principle.

Figure 1 is a longitudinal section of a car floor and of the draft-gear. Fig. 2 is a horizontal section of Fig. 1, taken on the central line of the draw-bar of the coupler. Fig. 3 is a half sectional end view and a sectional view taken through the spring-pocket. Fig. 4 is an edge view of an equalizer-yoke. Fig. 5 is a longitudinal sectional view in elevation of the draft-sills. Fig. 6 is a top plan view of the draft-sills. Fig. 7 is a half end and half sectional view of Fig. 5. Fig. 8 is the triangular frictional block. Fig. 9 is the front frictional block. Fig. 10 is the rear frictional

block. Figs. 11, 12, and 13 are views of a modified construction of the draft and buffing gear in which a single or compound spring is employed.

Referring to the several figures, the numeral 1 designates the central stringers of the car-frame, which may be of any approved construction; 2, the end sill; 3, the buffer-block; 4, the metallic draft-sills, made of any suitable metal; 5, the carry-iron, cast integral with the draft-sills; 6, the angular chafing-plate, also cast integral; 7, the top tie-plate, which unites the draft-sills and which plate may be strengthened by ribs, as shown; 8, the bottom tie-plates, both said top and bottom plates being cast integral with the sills in this example; 9, the spring cage or barrel, cast integral and strengthened by suitable ribs; 10, the hollow bolt-columns of the sills; 11, the central slots in each of the sills; 12, the front elongated slots in the sills; 12', the rear elongated slots in the sills; 13, the ribs extending outwardly from the slots for strengthening the same and furnishing ample frictional surfaces for the pins; 14, the draw-bar of the coupler; 15, an elongated slot in the draw-bar; 16, the front friction block or wedge; 17, the inclined face or surface of the block; 18, an elongated slot in the block; 19, the triangular friction block or wedge; 20, the front frictional face; 21, the rear frictional face; 22, the bottom or horizontal frictional face or surface; 23, the rear friction block or wedge; 24, the inclined frictional face or surface; 25, the slot in the block; 26, the frictional under face of the top tie-plate, which is engaged by the top surfaces of the end wedge-blocks; 27, the spring-cap having a top frictional surface engaged by the lower surface of the triangular block; 28, the coiled or helical springs; 29, the draw-bar yokes located, as shown, each side of the blocks; 30, the end slots in the yokes; 31, the central elongated slot in each of the yokes; 32, the equalizing-pins; 33, the cotter-pins, and 34 are the bolts which secure the draft-sills to the stringers, end sill, and buffer-block.

The drawings show the entire rigging complete as it is applied to a car ready for service.

The *modus operandi* is as follows: When an outward pull or draft is made on the draw-

bar of the coupler, the front equalizing-pin imparts movement through the yokes to the rear equalizing-pin. While the central oblong slot in the yokes is traveling over the 5 central equalizing-pin, the yokes at the same time pull the frictional wedge or block 23 against the triangular wedge 19. Wedge 16 being immovably held in position by the central equalizing-pin, the triangular wedge 19 10 is forced downwardly upon the spring or springs, and simultaneously there is caused a frictional resistance at the top surface of wedge 23 against the top tie-plate and on both inclined faces of the triangular wedge, as well 15 as a horizontal sliding frictional movement of one inch upon the spring-cap. When the first jar or strain has been imparted to the spring or springs and the same have been compressed to the extent of one inch, the wedge 20 23, as well as the front and rear equalizing-pins, will have traveled the distance of one and three-fourths inches, which gives all the equalizing-pins a bearing against the draft-sills, thereby preventing any further strain 25 upon or compression of the spring or springs. When the draw-bar of the coupler is forced rearwardly in buffing against the rigging, the oblong slots in both the draw-bar and wedge 16 travel over the front and central equalizing-pins, the wedge 16 being forced against the triangular wedge or block. The rear wedge 30 being immovably held in position by the rear equalizing-pin, it serves as a stop or abutment for the triangular wedge, thereby forcing the 35 triangular wedge downwardly upon the spring or springs, causing a frictional resistance at the top of wedge 16 against the top tie-plate and on both inclined faces of the triangular wedge, as well as a horizontal sliding frictional resistance or movement of one inch 40 upon the spring-cap. When the first jar or strain has compressed the spring to the extent of one inch, the front wedge and draw-bar will have traveled one and three-fourths 45 inches over the front and central equalizing-pins, which causes all of the equalizing-pins to have a solid bearing against the edges of the slots of the draft-sills, thereby taking the strain and preventing further compression of 50 the spring or springs. When either a push or draft is made on the coupler and draw-bar, frictional resistance at four places is occasioned—viz., at the top of either of the wedges 16 or 23 and the under surface of the top tie-plate, depending entirely upon which direction 55 the draw-bar moves, as one of the wedges is stationary, while the other is in motion. The additional three frictional resistances are on the three sides or faces of the independent 60 triangular-shaped wedge or block, and these frictional resistances prevent any perceptible recoil of the spring or springs.

The entire draft-rigging can be applied, replaced, or repaired very quickly and with facility. It can be applied by simply bolting the draft-sills to the stringers of the car. The 65 spring or springs may be placed in position

by the insertion of the same through the back of the draft-sill pocket or through either side of the cage or barrel portion of the rigging. 70 The spring-cap may be adjusted by the insertion of the same through the back or front of the pocket. The triangular-shaped wedge may be passed through the back or front of the pocket on top of the spring-cap. The 75 yokes may be adjusted on either side of the wedges through either the back or front of the pocket. The wedges 16 and 23 may be adjusted in position through the ends of the 80 pockets and where they are held by the equalizing-pins, which latter can be put in from either side of the draft-sills through the oblong slots or holes in the draft-sills, draw-bar, yokes, and wedges. The draw-bar of the 85 coupler is adjusted by inserting the same between the front ends of the draft-sills, which include the carry-iron and buffer angle-plate, and between the yokes, where it will contact with the front square face of the wedge 16. Then the front equalizing-pin is inserted from 90 either side through the oblong slots in both sides of the draft-sills and through the yokes and draw-bar. Each of the equalizing-pins is held in position by spring-cotters on each 95 side, as shown on the drawings. Any of the above-mentioned parts, including the coupler, may be easily replaced by the removal of either of the three equalizing-pins, as may be required, thereby reducing both the time and labor necessary in removing or replacing 10 any of the constituent parts as compared with the time and labor requisite in adjusting the parts of other well-known types of draft-rigging.

From the foregoing description, taken in 105 connection with the drawings, it becomes obvious that we have produced a draft and buffing gear or rigging which fulfills all the conditions set forth as the purpose and end of our invention.

While we have illustrated and described only two examples of the physical embodiment of our invention, we do not thereby intend to limit the scope of the same to the said specific examples, inasmuch as the principle may be applied in other forms and by other modes. Parts of the means shown may be used to the exclusion of other parts and substitutions for certain elements be made at will, also other dimensions and shapes of the 115 elements be devised and parts shown integral be made in two or more pieces and other changes, modifications, omissions, additions, and alterations be introduced at the choice of the manufacturer without constituting substantial departures.

What we claim as new, and desire to secure by Letters Patent, is—

1. The combination in a draft and buffing gear, of a coupler; a plurality of separate metallic movable elements frictionally engaging non-movable elements; and a spring or springs holding said elements in frictional contact; said spring or springs being located

in a horizontal plane at one side of and parallel with the plane of the movable elements and adapted to be compressed in a vertical plane in drawing or buffing.

5 2. The combination in a draft and buffing gear having three separate movable frictional elements, of a coupler; one movable element frictionally engaging a non-movable element and a movable element; and a spring or springs located in a horizontal plane at one side of the plane of the movable elements and adapted to be compressed in a vertical plane by the last-mentioned movable element in the act of drawing.

15 3. The combination in a draft and buffing gear having three separate movable elements, of a coupler; one movable element frictionally engaging a non-movable element and a movable element; and a spring or springs located in a horizontal plane one side of the plane of the movable elements and adapted to be compressed vertically by the last-mentioned movable element in the act of buffing.

25 4. The combination in a draft and buffing gear, of a coupler; two separate movable elements in frictional engagement with a non-movable element and a vertically-movable element; and a spring or springs adapted to be compressed by the movement of the last-mentioned movable element.

30 5. The combination in a draft and buffing gear, of a coupler; a triangular movable friction block or wedge; a spring or springs; and two separate movable elements for engaging the said block and causing it to compress the spring or springs in the act of drawing or buffing.

6. The combination in a draft and buffing gear, of a coupler; a triangular movable friction-block; a separate movable block located in the rear of the triangular block and having a surface engaging one of the surfaces of the triangular block; and a spring or springs adapted to be compressed by the triangular block in the act of drawing.

45 7. The combination in a draft and buffing gear, of a coupler; a triangular movable friction-block; a separate movable block located in front of the triangular block and having a surface engaging a surface of the triangular block; and a spring or springs adapted to be compressed by the triangular block in the act of buffing.

8. The combination in a draft and buffing gear, of draft-sills having slots; equalizing pins located in the slots; draw-bar yokes located between the draft-sills; a draw-bar and coupler; movable friction-blocks; and a spring or springs; two of the pins having lon-

gitudinal movement within the slots of the 60 sills.

9. The combination with a draft and buffing gear, constructed substantially as described, of a triangular block, a front block with an inclined face, a separate rear block 65 with an inclined face, and a spring, said triangular block being movable in a vertical plane in drawing and buffing and adapted to compress the spring vertically.

10. The combination with a draft and buffing gear, constructed substantially as described, of a triangular friction-block, a front block, a rear block, a spring or springs, slotted yokes, slotted draft-sills, pins located within the slots of the yokes and draft-sills, and a 70 draw-bar and coupler.

11. The combination with a draft and buffing gear, constructed substantially as described, of slotted yokes, draft-sills having slots, equalizing-pins in the slots of the sills, 80 friction-blocks, a spring, and a draw-bar.

12. The combination in a draft and buffing gear, of slotted draft-sills; slotted friction-blocks; a slotted draw-bar; slotted yokes; pins within the slots of the draft-sills, blocks, 85 draw-bar and yokes; and a spring adapted to be compressed by the movement of one of the friction-blocks.

13. The combination with a draft and buffing gear, of two draft-sills each having three 90 slots, the end slots being elongated; a top plate 7 uniting the sills; a spring-cage united to the two draft-sills; slotted friction-blocks; a slotted draw-bar; slotted yokes; and a spring and equalizing-pins; said pins being located 95 within the slots of the several slotted elements.

14. The combination with a draft and buffing gear, of draft-sills having slots 12, 11, 12'; a slotted draw-bar; slotted blocks; a spring; 100 slotted yokes located between the draft-sills; and three pins 32, the front and rear pins being movable within the slots in the draft-sills.

15. The combination with a draft and buffing gear, of slotted draft-sills; slotted yokes; 105 slotted friction-blocks; equalizing-pins passed through the several slotted elements; a spring or springs; and a draw-bar and coupler; said slotted yokes being located between the friction-blocks and draft-sills.

In testimony whereof we affix our signatures in presence of two witnesses.

I. ORVILLE WRIGHT.
